UNITED STATES PATENT OFFICE.

GEORGE L. TYLER, OF LYNN, MASSACHUSETTS.

MACHINE FOR SPLITTING LEATHER.

SPECIFICATION forming part of Letters Patent No. 242,079, dated May 24, 1881.

Application filed March 5, 1881. (No model.)

To all whom it may concern:

Be it known that I, GEORGE L. TYLER, of Lynn, in the county of Essex and State of Massachusetts, have invented a new and useful Im-
5 proved Device for Splitting Leather, of which the following is a full, clear, and exact description, reference being made to the accompanying drawings, which form a part of this specification, like letters indicating like parts in the
10 different figures thereof.

Figure 1 of the drawings is an isometrical projection, illustrating my invention in complete working order. The lower feed-roll, A', which is exactly like the upper feed-roll, A, is
15 partially hidden in this view by the adjustable sliding divided holder C, with its divided part C', and by the knife or cutter B. Fig. 2 is a transverse vertical section cut on the line x x of Fig. 1. Fig. 3 shows a piece of leather before
20 it is split; and Fig. 4 shows the same piece split nearly in two, but with the two parts thereof held together at the line y y.

The mode of splitting leather by the use of my invention, so as to leave the two parts of
25 the split piece attached on the line y y, Fig. 4, by a connection of leather of the desired thickness, forms the leading feature of my invention, and the manner of regulating the thickness of
30 said connection by means of the adjustable sliding divided holder C, whereby the knife or cutter B is moved longitudinally from or toward the guide E, will be hereinafter fully described.

My invention, as a whole, consists of the
35 mode of splitting leather by means of an adjustable sliding divided holder with an adjustable knife or cutter attached thereto, and with the guide E, the whole in combination with two ordinary adjustable feed-rolls. The invention
40 is of use, primarily, for utilizing small and perhaps otherwise useless pieces of leather in making center lifts for the heels of boots and shoes, so that said lifts shall each be in one piece and in proper and convenient form for
45 use.

The two feed-rolls A and A' are constructed as shown in Figs. 1 and 2, their journals being held in the ordinary journal-boxes a, said journal-boxes being arranged so as to slide up and
50 down in the two standards A² by any suitable and well-known means. The four spiral springs

a² are used as the well-known means of adjusting the feed-rolls for the accommodation of leather of varied thickness. The two upper springs are moved by means of the two screws 55 a³, said screws being turned by the well-known means of inserting a turning-rod in the openings a⁶, and are held by the nuts a⁴. The two bearings a⁵ form bearings both for said upper springs a² and said screws a³, the tops of the 60 two standards A² forming the upper bearings for said upper springs, and the bases of the two standards A² form the lower bearings for the two lower springs a², with the lower journal-boxes, a, as the upper bearings of said lower 65 springs; but I do not claim the feed-rolls or their arrangement and means of adjustment in the standards A² as new in the abstract, but merely in combination with the adjustable sliding holder, the adjustable cutter, and the 70 guide, to be hereinafter described.

C is the adjustable sliding divided holder hereinbefore referred to. Said holder is fastened to the two standards A² by means of the two screws c, and the holder may be adjusted 75 up and down without removing the screws c, because of the elongated slots c³. This holder is a divided one, because the part C' thereof can be taken off of the main part C by removing the screw c', and it is a sliding holder 80 in so far as that when the sliding part C' is fastened to the main part of the holder C by means of the screw c' the said sliding part C' can be moved longitudinally, because of the elongated slot c²; and the knife or cutter B being 85 attached to said part C' of the holder C by means of the two screws b, said knife moves longitudinally when said part C' is moved. The elongated slots b' enable the operator to adjust the knife B by moving said knife forward and back. 90

E forms a guide and a bearing for the edge of the piece of leather during the process of splitting.

The two gears G, it is obvious, mesh together for the purpose of revolving the two feed-rolls 95 A and A' when the power is applied. The power may be applied in any known and suitable manner, but should, of course, be so applied as that the two gears G will mesh properly, and so that the two feed-rolls A and A' will 100 retain their proper relative positions when said rolls are adjusted for perfect work.

Before describing the operation of the invention I will say that Fig. 1 of the drawings shows the back of the machine as practically operated, and in the use of the words "back" and "front," as hereinafter made, those words should be understood as applied to the machine when in practical operation.

The knife B should be so adjusted by taking advantage of the elongated slots b' that the edge of the knife (which edge extends the entire length of the front of said knife) shall be a very little back of a line drawn between the two feed-rolls, longitudinally of said rolls and along the center thereof, so that the feed rolls may be enabled to get a good hold of a piece of leather before the edge thereof reaches the knife.

The object of the four springs a² is to secure such adjustment of the feed-rolls A and A' that leather of varied thickness will always be split at the center thereof, both the upper and lower feed-rolls, A and A', respectively being provided with springs a², as shown in the drawings.

The knife or cutter B is not quite as long as the distance from the end of the main holder C, designated C², to the guide E, so as to leave play for sliding the part C' of said main holder by taking advantage of the elongated slot c².

A piece of leather is first cut into a shape to conform to the contour of one half of a sole or heel blank, when centrally and longitudinally divided, as shown in Fig. 3 of the drawings. Said piece is then inserted between the feed-rolls A and A' from the front of the machine, with the edge y' of said piece bearing against the face of the guide E. Said piece of leather is split along its entire length, and passes out of the back of the machine, with one side of said

now split piece above and the other below the knife B. The space between the end e of the

knife B and the guide E is regulated in width by moving the sliding part C' of the main holder C longitudinally, in the manner before described.

It will be readily seen that if a piece of leather is split in the manner before described, the guide E, being used as a guide to and bearing for said piece of leather, the connection of leather which holds the two split parts together, which connection is designated by the line y y in Fig. 4, will be of a thickness proportionate to the width of space between the end e of the knife B and the face of the guide E, so that said thickness of connection may be regulated by adjusting the knife B by means of the movable sliding part C', in the manner hereinbefore fully described.

What I claim as new, and desire to secure by Letters Patent, is—

1. An improvement in the art of forming boot and shoe sole and heel blanks, consisting in cutting or shaving a piece of leather into the outline or contour of half of a sole or heel blank, when divided centrally and longitudinally, then splitting such prepared piece of leather, leaving a connecting or hinged portion, then turning the divided portions outwardly, thus producing a sole or heel blank of full width, having the desired contour, all substantially as set forth.

2. The adjustable divided holder C, with movable sliding part C', the knife or cutter B, and the guide E, in combination with the two feed-rolls A and A', said rolls being provided with the adjusting-springs a², all constructed and arranged substantially in the manner described and shown, and for the purpose set forth.

Witnesses: GEORGE L. TYLER.
